UNITED STATES PATENT OFFICE.

JAMES SCRIPPS BOOTH, OF DETROIT, MICHIGAN.

INTERNAL-COMBUSTION ENGINE.

Application filed November 6, 1924. Serial No. 748,119.

To all whom it may concern:

Be it known that I, JAMES SCRIPPS BOOTH, a citizen of the United States, residing at Detroit, in the county of Wayne and State of Michigan, have invented certain new and useful Improvements in Internal-Combustion Engines, of which the following is a specification.

This invention relates to internal combustion engines and has for its object a design of intake and exhaust manifold and carburetor which gives adequate fuel charges to each cylinder, and which properly pre-heats the charge without encountering the difficulty of transferring the exhaust from one side of the cylinder block to the other.

Of course, in an L-head motor of the poppet valve type, the exhaust and the intake are both on the same side, but in a T-head motor of the poppet valve type, and in nearly all sleeve valve motors the exhaust and intake are on opposite sides of the cylinder block. It is not very convenient to transfer the exhaust gases from one side of the cylinder block to the other for forming a so-called hot-spot on the carburetor or the intake manifold. Such a transference induces difficulties in a motor design which it is the object of the present invention to overcome.

It is also desirable in an engine having a large number of cylinders, eight or more, to have two carburetors for supplying the fuel charges as this insures a more even distribution of the fuel charge and a better flow of power. I have therefore so coupled and laid out the arrangement of the duplex carburetor as to completely eliminate the difficulty of transferring the hot gases from one side of the cylinder block to the other.

I have further solved the difficulty introduced by a carburetor on each side of the cylinder block when an air cleaner is used. I surmount the air cleaner on top of the engine cover and connect the interior of the engine cover with each carburetor by suitable conduits. This eliminates the necessity of an air cleaner on each side, or piping running over or around the engine block.

Referring to the drawings:

Fig. 1 is a plan view of my improved motor design.

Fig. 2 is a side elevation of the same.

Fig. 3 is a cross section of the motor.

Fig. 4 is a longitudinal section of the

same, taken substantially in the plane of the intake and exhaust ports.

The so-called straight eight places a large task on a single carburetor and it is found in actual practice that it is desirable to use two carburetors to prevent the starving of the end cylinders. In place of supporting these carburetors *a—a* on the same side of the cylinder block as is the customary practice, I place one carburetor *a* on one side of the cylinder block at the front and the other carburetor *a* on the opposite side of the cylinder block at the rear. Preferably, these carburetors are located one midway between each set of cylinders fed by such carburetor, here shown as sets of four. This assures a fairly equal distribution of the mixed fuel and air to all the cylinders. This lay-out is well illustrated in Fig. 4, and the details will be apparent without specific enumeration. The manifold *b* divides at the center and each end feeds a pair of cylinders which here happen to be shown as two-ported cylinders having sleeve valves.

The same arrangement obtains on the rear division of four cylinders. Now it will be noted that each cylinder has two exhaust ports on the opposite side and these are connected through separate passageways *c* with the exhaust manifold *d*, which has a plurality of branches *e*. Hence, the exhaust gases from the front set of cylinders serves to pre-heat the fuel charge for the rear set of cylinders, while the exhaust gases for the rear set of cylinders is carried by the manifold forward to the front intake manifold, which is provided with a suitable jacket *f* to "hot-spot" the intake manifold. It will be apparent that these exhaust gases can be used either to pre-heat the gases in the manifold or to form a hot-spot around the carburetor, although as here illustrated, only the hot-spot on the manifold is shown.

In the higher grade cars it is now desirable to employ an air cleaner to separate out the suspended particles of dust and grit which would otherwise be drawn into the cylinders. With a carburetor on each side, either two air cleaners or some form of pipe over or around the cylinder block would be required, but obviously undesirable. I have solved the difficulty by utilizing the chamber under the usual cover plate *g* as an air chamber. The air cleaner *h* screws into

the top of this cover plate. This cover plate is drawn down over a pair of air conduits or elbows *j*, the cover plate being notched for this purpose. A pair of hand-operated screws *i* are used to hold the cover plate in position. The air is drawn in through the air cleaner. It is then distributed around the top of the cylinder and thence to the carburetor. This particular form of distribution has also a functional value in connection with the performance of the engine, as obviously the cylinder top gets more or less hot and the air is drawn into the carburetor in slightly tempered condition. This in cold weather approximates more nearly a summer heat, which is a beneficial heat condition of the air as it is not unduly expanded, as is the case if the air is unduly heated by some kind of a stove along the exhaust manifold. Furthermore, the circulation of air which is drawn in at considerable velocity around the plugs has a beneficial effect in keeping the plugs cool.

This invention has been explained in connection with a straight-eight motor, but obviously the number of cylinders so far as the broad principles of the invention are concerned, is immaterial.

What I claim is:

- 20 1. In an internal combustion engine, a plurality of cylinders divided into a front set and a rear set, the front set arranged for and provided with manifolding means for taking in the charge on one side and exhausting on the other side, and the rear set being arranged for and provided with manifolding means for exhausting on the one side and taking in the charge on the other side just conversely to the front set, together

with connections whereby the exhaust gases of one set of cylinders heats the incoming fuel mixture of the other set of cylinders on the same side without being caused to pass to the opposite side of the cylinder block.

2. In an internal combustion engine, the combination of a plurality of aligned cylinders divided into a front and a rear set, the front set arranged for and provided with manifold means to take in the fuel charge on one side and exhaust on the other side, while the rear set of cylinders is conversely arranged and provided with manifolding means to exhaust on the one side and take in the fuel charge on the opposite side, together with connecting conduits in the manifolding for taking the exhaust and leading the same into proximity to the intake charge on the same side, whereby the one set of cylinders furnishes exhaust gases for heating the fuel charge of the other set of cylinders on the same side of the block.

3. In an internal combustion engine, the combination of an engine block provided with a plurality of cylinders divided and having carburetor connections on each side of the cylinders, a separate carburetor on each side of the cylinders joined with said connections, a cover plate for the cylinder block, air intake conduits leading from the interior of the cover plate to the carburetors, and an air cleaner surmounted on said cover plate for purifying the air that is admitted to the interior of the cover plate and thence to both carburetors.

In testimony whereof I have affixed my signature.

JAMES SCRIPPS BOOTH.
